CLAIM

(22) Filed: **May 2, 2013**

The ornamental design for a hanger, as shown and described.

(30) **Foreign Application Priority Data**

DESCRIPTION

Nov. 5, 2012 (KR) 30-2012-0052714

FIG. 1 is the front/right-side/top perspective view of a hanger showing our new design;

(51) **LOC (10) Cl.** **15-07**

FIG. 2 is the front-side elevational view thereof;

(52) **U.S. Cl.**

FIG. 3 is the rear-side elevational view thereof;

USPC **D15/89**

FIG. 4 is the left-side elevational view thereof;

(58) **Field of Classification Search**

FIG. 5 is the right-side elevational view thereof;

USPC D15/79, 81, 85, 89, 91; 223/85-98;

FIG. 6 is the top-side plan view thereof;

211/10, 71.01, 72, 73, 78, 80, 83, 85,

FIG. 7 is the bottom-side plan view thereof;

211/85.2, 87.01, 90.01, 113, 135; 248/95,

FIG. 8 is the front/right-side/top perspective view thereof shown in an alternate configuration; and,

248/99, 100, 101, 510, 682, 689;

FIG. 9 is the second front/right-side/top perspective view thereof shown in an environmental state.

D6/315-328, 512, 553, 567, 572, 574;

The broken lines shown represent unclaimed subject matter

312/321.5; 62/377

and form no part of the claimed design.

See application file for complete search history.
